UNITED STATES PATENT OFFICE.

CHARLES G. LEA, OF ATCHISON, KANSAS.

RAILROAD-FROG.

SPECIFICATION forming part of Letters Patent No. 394,379, dated December 11, 1888.

Application filed July 3, 1883. Serial No. 99,936. (No model.)

To all whom it may concern:

Be it known that I, CHARLES G. LEA, of Atchison, in the county of Atchison and State of Kansas, have invented an Improvement in the Manufacture of Railroad-Frogs, Railroad-Crossings, and Similar Devices Used in the Tracks of Railroads; and I hereby declare the following to be a full, clear, and exact description of the same, reference being had to the accompanying drawings, making part of this specification, in which—

Figure 1 is a perspective view of a railroad-frog made after my invention. Fig. 2 is a vertical cross-section of the same on the line x x of Fig. 1. Fig. 3 shows a railroad-crossing made after my invention.

The object of my invention is to provide a railroad-frog, railroad-crossing, or similar device made without any drilling or use of bolts or wedges to hold the parts together, and yet have a safe and substantial union between the parts, and a supporting bed-plate integral with the casting holding the pieces of rolled rail together, the pieces of rail having previously been properly shaped, as hereinafter fully set out.

In order that those skilled in the art may make and use my invention, I will proceed to describe the manner in which I have carried it out.

In the said drawings, A A' A'' represent the rails of a frog. These rails may be of rolled steel or of rolled iron and of any required form. In a mold made in the usual manner, provided with suitable cores, the rolled rails A A' A'', previously shaped, are placed in their proper relative positions, said rails being cold. Molten cast-iron is then poured into the mold and spreads beneath the base-flanges of the rails A A' A'', and rises up around and between the bases of the rails and the webs to such a height as not to interfere with the flanges of the car-wheels, and forms a plate, B, in which is firmly embedded

the rails A A' A''. In cooling, the plate B 45 shrinks close around all the lower parts of the rails and holds them rigidly, forming a solid bearing for the rails, and no drilling or bolts or wedges required.

Heretofore the rails or rail-sections have 50 been heated to a red or welding heat before being placed in the mold. My method of manufacture differs therefrom in employing the rail-sections cold, the object being to have the molten metal shrink about and in contact 55 with the rails as it cools, thus securing a firm union and reducing the cost of manufacture.

I am aware that spacing-pieces have been heretofore cast in frogs to hold the wings or guard-rails at proper distances apart, the said 60 spacing-pieces being cast around bolts; but my invention has no such construction.

I am also aware that heretofore pieces of straight rails have been inserted in molds to 65 about against a casting of a frog or similar device, and hence make no broad claim to inserting rails in a mold designed to receive molten metal; but,

Having thus described my invention, what I claim as new, and desire to secure by Letters 70 Patent, is—

1. In a railroad frog or crossing, the combination, with rolled rails having base-flanges, of a base-plate cast beneath and around the base-flanges and upward on both sides of the 75 lower portions of the rail-webs, as and for the purpose set forth.

2. That improvement in the manufacture of railroad frogs and crossings which consists in casting a metal plate around and beneath 80 the lower portions of rail-sections having base-flanges and placed cold and in proper position within a mold, substantially as described.

CHAS. G. LEA.
